Primary Examiner — Sandra S Snapp*Assistant Examiner* — M. F. B.(74) *Attorney, Agent, or Firm* — Rabin & Berdo, P.C.(57) **CLAIM**

The ornamental design for a game device, as shown and described.

DESCRIPTION

FIG. 1 is a front perspective view of a game device; FIG. 2 is a rear perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The broke lines in the drawings depict portions of the game device that form no part of the claim design.
